Patented Jan. 1, 1918.

UNITED STATES PATENT OFFICE.

ERNEST HUTTON, OF WAYLAND, KENTUCKY.

BLASTING-GUN.

1,252,117.

Specification of Letters Patent.

Patented Jan. 1, 1918.

Application filed March 28, 1917. Serial No. 158,073.

To all whom it may concern:

Be it known that I, ERNEST HUTTON, a citizen of the United States, residing at Wayland, in the county of Floyd and State 5 of Kentucky, have invented certain new and useful Improvements in Blasting-Guns, of which the following is a specification.

This invention relates to that class of blasting devices that are arranged both to 10 choke the bored hole in the inner end of which a blasting-charge is placed and thereby to cause the full force of the explosion to operate in breaking the material in which the hole is formed and to fire the charge.

15 More particularly, it is an object of the invention to provide, for holding the device in the bore, improved expandable means that by manual operation is tightened against the wall of the bore before explosion of the 20 charge and that is caused further to press against the wall by the force of the explosion, whereby the bore is choked and the device is restrained from being blown backwardly when the charge is fired and it is 25 caused to fall with the broken-off material.

The device to which this invention is directed includes a rod having slidable upon one of its end portions a barrel carrying a firing-terminal arranged to hold an explosive 30 cartridge.

When read in connection with the description herein, the details of construction and arrangement of parts contemplated by the invention will be apparent from the accompanying drawing, forming part hereof, 35 wherein an embodiment of the invention is disclosed, for purposes of illustration.

While the disclosures herein now are considered to exemplify a preferable embodiment of the invention, it is to be understood that it is not the intention to be limited necessarily thereto in interpretation of the claims, as modifications within the limits of the claims can be made without departing 45 from the nature and spirit of the invention.

Like reference-characters refer to corresponding parts in the views of the drawing, of which—

Figure 1 is a plan view;

50 Figs. 2-2^a is a longitudinal sectional view;

Fig. 3 is a transverse sectional view on the line 3-3, Fig. 2^a;

Fig. 4 is a transverse sectional view on 55 the line 4-4, Fig. 2^a, and Fig. 5 is a view

of a part of the shank portion of the rod, showing one of the slots thereof.

The gun includes a rod 5 having at its outer end a head 6 provided with a turning-handle 7, and the rod is formed with a centrally-disposed bore or passage 8 extending from a place adjacent to the head to the other or inner end. The rod is formed intermediately of its ends with an enlarged tapered portion 9 circular in cross section 60 that gradually decreases in diameter toward the inner end, and continuing therefrom to the inner end is a barrel-holding terminal shank portion 10 of uniform diameter. The inner end portion 10 of the rod is formed 70 with a plurality of longitudinally-disposed slots 11, having lateral offsets 11^a at the ends adjacent to the end of the rod.

A barrel portion 12 in the form of a tubular member is slidable freely and longitudinally on the shank portion 10 of the rod, and relative movement of the parts is limited by pins 13 extending into the slots 11. A tubular portion is formed integrally with and extends from the barrel over the tapered 75 part 9 of the rod and interiorly conforms approximately to the shape of that part. In order that this tubular portion, when it is moved in one direction longitudinally on the rod, may be permitted to expand and to be 80 pressed against the wall of the bored hole, it is slotted longitudinally, whereby fingers 14 are provided that are formed integrally with and extend backwardly from the barrel. The free end portions of the fingers 90 85 are exteriorly roughened or corrugated, preferably with screw-threads, as shown at 15, in order that they may grip the wall of the bored hole. The fingers are reduced in thickness at a place adjacent to the barrel, 95 whereby there is provided an annular groove for asbestos or other suitable expandable packing 16. The barrel is formed with an exterior annular groove 17, in which packing-rings 18 are disposed. The packing 16 100 and 18 closely fits the wall of the bore in which the gun is inserted.

The barrel is interiorly screw threaded in its free end portion to receive the threaded portion of a pointed terminal 19, having a 105 transverse opening 20 through its free end, the terminal being adapted to extend into the casing of, and thereby to hold, an explosive cartridge A.

Of an electric circuit including a battery 110

or other suitable source of electricity and a switch (not shown) one wire 21 is grounded in the rod 5 at or near its head, and the other wire 22 is adequately insulated and 5 leads into the rod and through the bore 8, the barrel 12, and terminal 19 to the opening 20 in the latter where it is uninsulated and constitutes a spark-point.

When the gun is to be used, the explosive 10 cartridge is placed on the terminal 19, and the cartridge and gun are placed in a bored blast-hole and the cartridge pushed by the gun to the bottom or inner portion of the hole. At this time, the barrel is extended from 15 the rod to the extent permitted by the slots 11 and pins 13, and the pins seat in the offsets 11^a of the slots whereby the rod is prevented from being pushed farther into the barrel. During insertion of the gun, if it 20 fits the wall of the hole too tightly to permit easy movement, it may be forced inwardly by tapping on the head of the rod, or it may be screwed inwardly by turning the rod in a direction to keep the pins in 25 the offsets of the slots. After the charge is placed to the desired depth in the hole, the rod is turned in the reverse direction to bring the pins out of the offsets and thereby to permit the pins to slide in the slots and 30 the rod to be pushed farther into the barrel. The rod then is pushed inwardly, and the wedging action of the inclined portion thereof against the fingers 14 causes those fingers tightly to grip the wall of the hole; 35 and, if desired, further wedging action may be effected by tapping on the head of the rod. Expansion of the fingers causes the packing 16 also to expand against the wall of, and more effectively to choke, the hole. 40 Thereafter, the switch of the electric circuit is closed and a spark thereby caused to jump across the space between the end of the wire 22 in the opening of the pointed terminal 19 and the material of that terminal, which latter is connected with the other wire of the circuit by that wire being grounded in the rod 5. This explodes the charge. The backward or outward push on the barrel resulting from the explosion 45 causes the barrel to recoil farther on the rod and further to expand the fingers 14, thereby effecting a tighter grip of the fingers on the wall of the bore and preventing the gun from being driven backwardly out 50 of the material being blasted. The arrangement thus permits a recoil of the rod and gradually stops that movement, and the strain on the gun as a result of the explosion is less, therefore, than if the rod were 55 held rigidly in the hole. Moreover, as the backward movement of the rod gradually is stopped, the tendency to break the hold of the fingers on the wall of the hole is lessened and the gun is less liable to be blown from 60 the hole than if it were held rigidly therein. 65

Thus the gun remains in the hole if the charge does not shoot down the material below the hole entirely out to the face of the material, and it falls down with the material if all of it is shot down. In case the 70 gun remains in the hole after the charge is fired, the rod may be turned in a direction the reverse of that for insertion and moved outwardly with respect to the barrel, whereby the grip of the fingers on the wall of the 75 hole is loosened, and then the gun may be pulled out of the hole.

Having thus described my invention, what I claim as new, and desire to secure by Letters Patent, is—

1. A blasting-gun comprising a rod having an intermediate portion that tapers gradually to less diameter toward its inner end and a shank, a barrel freely slidable longitudinally on said shank, an expandable 85 tubular portion extending from said barrel and arranged to be pressed against the wall of a hole on movement in contact with said tapered portion, and charge-firing means at the free end of said barrel. 90

2. A blasting-gun comprising a rod having an intermediate portion that tapers gradually to less diameter toward its inner end and a shank, a barrel freely slidable longitudinally on said shank, fingers extending 95 from said barrel and arranged to be pressed against the wall of a hole on movement in contact with said tapered portion, and charge-firing means at the free end of said barrel. 100

3. A blasting-gun comprising a rod having an intermediate portion that tapers gradually to less diameter toward its inner end and an inner terminal shank portion, a barrel freely slidable longitudinally on said shank portion, fingers extending from said barrel and arranged to be pressed against the wall of a hole on movement in contact with said tapered portion, packing around 105 said fingers expandable therewith, and charge-firing means at the free end of said barrel. 110

4. A blasting-gun comprising a rod having an intermediate portion that tapers gradually to less diameter toward its inner 115 end and an inner terminal shank portion formed with a longitudinally-disposed slot having a lateral offset, a barrel freely slid able longitudinally on said shank portion and having a pin coactable with said slot 120 and offset to limit respectively relative rotary and longitudinal movement of said rod and barrel, an expandable tubular portion extending from said barrel and arranged to be pressed against the wall of a hole on 125 movement in contact with said tapered portion, and charge-firing means at the free end of said barrel.

5. A blasting-gun comprising a rod having an intermediate portion that tapers 130

gradually to less diameter toward its inner end and an inner terminal shank portion, a barrel freely slideable longitudinally on said shank portion, an expansible tubular portion integrally formed with and extending from said barrel and arranged to be pressed against the wall of a hole on movement in contact with said tapered portion, and charge-firing means at the free end of said barrel.

6. A blasting-gun comprising a rod having an intermediate portion that tapers

gradually to less diameter toward its inner end and an inner terminal shank portion, a barrel freely slideable longitudinally on said shank portion, fingers integrally formed with and extending from said barrel and arranged to be pressed against the wall of a hole on movement in contact with said tapered portion, and charge-firing means at the free end of said barrel.

In testimony whereof, I affix my signature.

ERNEST HUTTON.
